CLAIM

The ornamental design for a boot and glove dryer, as shown and described.

DESCRIPTION

FIG. 1 is a perspective view of the boot and glove dryer.

FIG. 2 is a front elevational view of the invention.

FIG. 3 is a left side elevational view of the invention.

FIG. 4 is a back elevational view of the invention.

FIG. 5 is a right side elevational view of the invention.

FIG. 6 is a top plan view of the invention; and,

FIG. 7 is a bottom plan view of the invention.
